GIZZARD SPLITTER AND WASHER

Norton B. Crane, Goldenrod, and Nelson H. Dunn,
Tampa, Fla.

Application October 30, 1956, Serial No. 619,226

9 Claims. (Cl. 17—11)

This invention relates to a gizzard splitter and washer, and more particularly to a device in which the gizzards are carried by a rotating wheel and washed by internal flushing.

The gizzards of poultry and other fowl are considered to be a desirable and edible portion of the bird. However, it is a well known fact that they contain a certain amount of waste material which must be removed before the gizzards can be prepared for sale. In so preparing them manually, it is customary to slit the gizzard lengthwise, opening it throughout most of its width, and then wash the waste material out from inside of the gizzard. It will be apparent that the manual processing of gizzards in this manner is a slow tedious task, and that one individual will not be able to process a very large number of the gizzards at any one time.

Devices have been proposed which split and wash a gizzard mechanically, but most of them have caused a high percentage of rejections, either because the gizzards by reason of varying size have been damaged in handling the machine, or the machine has failed to completely wash the gizzard and therefore resulted in a great deal of reprocessing.

It is therefore a primary object of our invention to provide a device in which uniform pressure will be applied to all gizzards processed by the machine, regardless of their size or shape.

It is still another object of our invention to provide a washing mechanism which may be inserted inside of the gizzard after it is split to cause the water to be flushed outwardly therefrom.

Another object of our invention is to provide a plurality of washing stations, said washing stations adapted to move into the path of movement of the gizzard only when such gizzards are in position in the machine.

It is still another object of our invention to provide a plurality of impinging members, said members being adapted to adjust themselves automatically longitudinally with reference to the gizzards themselves.

Other and further features and objects of the invention will be more apparent to those skilled in the art upon a consideration of the accompanying drawings and following specifications, wherein is disclosed a single exemplary embodiment of the invention, with the understanding, however, that such change may be made therein as fall within the scope of the appended claims, without departing from the spirit of the invention.

In said drawings:

Figure 1 is a three-quarter view in perspective of a gizzard splitter constructed according to our invention.

Figure 2 is an enlarged front elevation of the mechanism of the gizzard splitter and washer, portions thereof being cut away to more fully disclose the structure.

Figure 3 is an enlarged side elevation, in cross section, of the device shown in Figure 2.

Figure 4 is a rear view of the drive mechanism taken at line 4—4 of Figure 3.

2

Figure 5 is an enlarged view in cross section of the impinging members, they being shown in fully retracted position.

Figure 6 is another view in cross section of the impinging members showing them in a fully extended position.

Figure 7 is a top view of a pair of holding blocks in cross section, showing the impinging members in varying degrees of extension in relation to a gizzard held therebetween and

Figure 8 is an enlarged view partially in cross section of the washing mechanism shown in Figures 1 and 2, the side wall of the casing being broken away.

Referring now to the drawings, and more particularly to Figure 2; the primary conveying mechanism includes a large circular plate 11 which has a plurality of stations 12, 13 and 14 about its outer circumference. This circular conveyor or wheel 11 is rotated by stages in a clockwise direction, the gizzards to be processed being held 15 in the individual stations about the circumference of the wheel. In the embodiment shown, there are 12 such stations. In operation, the gizzard is placed on the conveyor wheel at the top in station 12. It then moves clockwise with the wheel to a point where it comes in 20 contact with a circular knife 15, then through the washing stations 16 and 17, thence upwardly to the chute 18 where the gizzard is ejected from the machine.

These various steps will now be described in detail, together with the nature of the stations themselves.

Referring to Figure 3; it will be noted that the conveyor plate 11 carries a rim 19 which is spaced outwardly at some distance from the main plate. The holding stations, such as 12, comprise two L-shaped blocks 20 and 21. The impinging members such as 22, 23, 24, 25, 26

25 and 27 are carried in these L-shaped blocks. This is true with each succeeding station in the blocks on both the main wheel 11 and the rim 19. These blocks are so positioned that the impinging members are directed inwardly towards each other and it will be apparent that it is between these impinging members that the gizzard is held.

The nature of these impinging members is of the utmost importance. The blocks are provided with a longitudinal bore 28, Figure 5, and the pins, such as 22, are cylindrical in shape and adapted to slide longitudinally 45 within the mating bored opening. On the inner ends of these impinging members is a downwardly extending peg 29 which is received in a longitudinal slot 30 within the block. The impinging members are biased outwardly by 50 a spring member 31. It will be at once apparent that these peg members can be utilized to move the impinging members back and forth within the bore of the block, and it will be apparent in further description that these peg members are used to cause the stations to be opened 55 and closed and also to regulate the movement of the washing mechanism at the bottom of the conveyor wheel.

The structure of the point of the impinging members is another important feature of our invention. It will be noted that a shoulder surface is provided on the outer ends of the impinging members and that a small needle-like point 33 extends further outwardly from this shoulder portion. Referring to Figure 7 in which a gizzard is shown in position between a plurality of such impinging members, it will be seen that the shoulder prevents the impinging member from penetrating the gizzard to any greater depth than the length of the needle-like point, and that in the embodiment shown, wherein six impinging members are positioned in each block, that their depth of thrust varies in accordance to the shape and size of 60 the gizzard itself, that the centermost pins extend only slightly outwardly from the blocks, whereas those on either end of the blocks are extended to their full lengths.

In order to place the gizzard in position between the two blocks, as at station 12, it is necessary that the impinging members be fully retracted. This is also the case at station 34, at which point the gizzard is ejected from the machine by the chute 18.

This desired movement of the impinging members to a retracted point can be achieved by use of the peg 29. To secure this desired movement, we have provided a rail member 35 which extends for a portion of the arc of this conveyor between stations 34 and 12. As the wheel moves through this arc, the pins are biased outwardly by the rail 35 and the impinging members held in the retracted position. It is apparent, of course, that with the impinging members in this position, the gizzard held at 34 will drop down between the main wheel and the rim into the chute 18 and out of the machine.

At the top of the conveyor at station 12, the rail ceases and the impinging members are then permitted to slide inwardly. It is at this point that the operator inserts the gizzard, holding it only until the impinging members move into proper engagement.

It is desirable to move the wheel in a series of steps, rather than have it operate continuously. For that reason, we have provided a lever-actuated switch 80 having a long tongue-like portion 36 which extends between the main wheel and the rim and about the arc of the wheel from one station to the next, beginning at station 12. When the operator places the gizzard in position between the two blocks, he will at the same time be pushing the gizzard against this tongue-like lever which will cause the switch 80 to close and, in the embodiment shown, operate the solenoid clutch member 37 which is connected to the motor 38. The solenoid acts on a pin 39 between the two faces 40 and 41 of the clutch member.

As soon as the wheel has moved from station 12 to station 13 and the gizzard passes off of the end of the cone, the switch is again opened and the wheel stops. It will not be placed in action again until another gizzard is inserted in the top opening 42. Of course it is sometimes desirable to revolve the wheel, although no gizzard may be in the individual station. For that reason, we have provided an over-riding switch 43 which will actuate the clutch in the same manner as switch 80.

Referring now to the splitting operation itself; it will be noted that the rotary blade 15 which is powered by its own individual motor 15a is so positioned that it will not completely sever one side of the gizzard from the other. It will still leave a slight hinge portion 45 in the split gizzard.

The repeated insertion of gizzards at station 12 will cause all of the other stations to advance one position with each insertion. This will bring the stations past the rotary knife blade and into position above the first washing mechanism. This washing mechanism is another important feature of our invention. It is here that the gizzards are internally washed, this being accomplished by mechanism which will be further described in detail, adapted to move the water nozzle 46 upwardly between the severed portions of the gizzard and into the interior of the gizzard. This washing nozzle is rotated during the time it is still inserted, thereby causing water to be directed about the circumference of the interior of the gizzard, thoroughly flushing it on the inside, the water flowing outwardly and carrying with it all waste material. A second washing or rinsing nozzle 47 is also provided to operate in the same manner as 46.

The operation of the washing mechanism is such that the nozzles are not moved upwardly unless a gizzard is actually being held by the pin members. As has been previously described, the presence of a gizzard causes the pins to be held outwardly whereby they come into contact with a lever 63, as shown in Figure 3. This lever in turn is adapted to actuate the solenoid such as 48.

A similar lever arrangement on the second washing station actuates the second solenoid 49. These solenoids in turn move laterally, actuating shafts 48a and 49a which are slideably attached to rocker arms such as 50 and 60 as shown in Figure 8.

The two nozzles 46 and 47 are carried by vertically splined housings 51 and 52. These housings are adapted to slide up and down in relation to the non-rotating water inlets 53 and 54, a seal such as 54a being provided to prevent leakage of water. The outer ends of the lateral rods, such as 48a, are attached to the upper end of the splined housing. It will be apparent that the lateral movement of this rod will cause the rocker arm 50 to be turned, in turn elevating the outer end of the rod and consequently the splined housing to which it is attached, thus causing the nozzle 46 to move upwardly into the gizzard.

To impart rotary motion to these two nozzles and their respective housings, I have provided a motor 55 which powers the pulley 56 through means of a chain 56a, which in turn turns a smaller gear 56b. The second chain 57 is operatively connected to two sprockets 58 and 59 which are mounted by means of the aforementioned spline on the housings 51 and 52.

From the foregoing description, it will be apparent that it would not be desirable to have these nozzles move upwardly into the path of rotation of the stations unless there was actually a gizzard in position in the station. Otherwise the nozzles might come into contact with the impinging members and cause a stoppage. Since the washing mechanism is operated by a separate motor, a separate switch 62 is provided to control this motor. This switch is the lever-operated type switch, the lever being shown in this embodiment at 63. It is L-shaped and has on its outer end a roller 64 which is adapted to engage the pegs 29. Obviously if these impinging members are fully extended because of the absence of any gizzard, the roller will contact the pegs at their innermost positions, thereby permitting the switch to remain in an opened condition; that if a gizzard is present in the station and the impinging members and their accompanying pegs are in a retracted position, the wheel will contact the peg in its outward point and close the switch, causing the motor to actuate the washing mechanism.

The entire structure, that is, the revolving wheel, the drive motors, and the like, are all housed in a rectangular cabinet or casing 65, the conveyor being carried on bearings such as 66 and 67 which are in turn carried by a cross member such as 68 and 69.

As previously stated, the drive mechanism for this device is adapted to move the stations from position to position in intermittent steps, permitting the gizzards to remain at one station long enough for the necessary operational actions, as for example the washing station. To secure this type movement, we have provided an intermittent drive commonly referred to as the Geneva type mechanical drive.

The clutch member 40, which is engaged to the motor 38 through the operation of solenoid 37, is in the form of a belt pulley and is adapted to drive a second larger pulley 40a. This pulley is mounted on a shaft 70 which is held in position by brackets 70a and 70b. Mounted on this shaft is the drive wheel 71 which in turn drives a larger wheel 72. It is this latter mechanism which is the Geneva type drive. The larger wheel has a plurality of slots 73, 74 and 75 about its outer circumference. These slots are adapted to receive the pin 76 on the drive wheel 71, this pin and drive wheel resembling a cam in that as the pin 76 engages one of the slots the larger wheel is turned in a clockwise direction for a predetermined distance. As the pin 76 is moved out of the slot, a groove 77 in the face of the drive wheel 71 engages two smaller pins, such as 78 and 79, causing the wheel 72 to be held

in a stationary position. This mechanism is more fully shown in Figure 7.

It will be seen, from the foregoing description, that we have provided a device in which gizzards are held gently in each of the individual stations, passed over a rotating knife, and then successively washed and rinsed by the introduction of water internally, then ejected from the machine at a predetermined point.

Although we have described a specific embodiment of our invention, it is apparent that modifications thereof may be made by those skilled in the art. Such modifications may be made without departing from the spirit and scope of our invention as set forth in the appended claims.

We claim as our invention:

1. In a gizzard washer, a shaft, a wheel rotatably mounted on said shaft said wheel comprising a disc having a rim mounted thereon and spaced apart therefrom, a plurality of opposed gizzard holding members positioned on the outer periphery of said disc and said rim, opposed impinging members slidably mounted in said holding members, and cam means operatively connected to said shaft for imparting an intermittent rotary movement to said wheel.

2. In a gizzard washer, a shaft, a wheel rotatably mounted on said shaft said wheel comprising a disc having a rim mounted thereon and spaced apart therefrom, a plurality of opposed gizzard holding members positioned on the outer periphery of said disc and said rim, opposed impinging members slidably mounted in said holding members, and means operatively connected to said shaft for imparting an intermittent rotary movement to said wheel, including a knife member adjacent said rotary wheel.

3. A device as set forth in claim 2, and further including washing means mounted adjacent and operatively connected to said rotary wheel.

4. In a device of the type described, a shaft, a circular wheel rotatably mounted on said shaft said wheel having a plurality of gizzard holding stations on the outer periphery thereof, said stations including a plurality of slidably mounted impinging members therein, said impinging members being adapted to hold a gizzard, splitting means positioned adjacent the outer circumference of said wheel, and a plurality of washing means mounted adjacent said wheel, said washing means including nozzles adapted to be moved upwardly into the path of rotation of said wheel and powered means operatively connected to said shaft for rotating said wheel.

5. In a device of the type described, a frame, a wheel rotatably mounted in said frame, power means operatively connected to said wheel adapted to impart intermittent motion thereto the outer periphery of said wheel including a plurality of gizzard holding stations comprising opposed block members having impinging members slidably mounted therein, and guide means on said frame adapted to move said impinging members longitudinally to permit the impinging of a gizzard thereon, and a knife member on said frame adjacent said wheel positioned to slit said gizzards, and a washing station positioned on said frame adjacent said wheel and adapted to wash said gizzards.

6. In a gizzard holding member for use with a gizzard washer of the type described, a plurality of opposed L-shaped blocks, a plurality of longitudinally disposed impinging members positioned in said blocks in opposed relation, a plurality of downwardly depending, actuating pegs mounted on said impinging members, guide members mounted on said gizzard washing device and adapted to engage said downwardly depending rods to cause said rods and said impinging members to be moved longitudinally outwardly from each other, and switch means mounted on said gizzard washer adapted to engage said

downwardly depending rod members, said switch means being adapted to actuate said washer.

7. In a device of the type described, a frame, a wheel rotatably mounted in said frame said wheel having a plurality of gizzard holding stations thereon, a washing station mounted on said frame adjacent said wheel and having a rotatably mounted nozzle therein, lever means operatively connected to said wheel and said holding stations for causing said nozzle to be extended substantially

10 inwardly radially of said wheel to intersect the path of movement of said gizzard holding stations when a gizzard is held therein.

8. In a gizzard splitter and washer, a frame, a wheel rotatably mounted in said frame, power means operatively connected to said wheel to cause the rotation thereof, a plurality of gizzard holding stations positioned on the outer periphery of said wheel, said stations including a plurality of opposed horizontally mounted impinging members having engaging pegs thereon, guide rail means positioned about the circumference of said wheel and adapted to engage said pegs to selectively cause outward movement of said impinging members to permit insertion of a gizzard therebetween, spring means adjacent each of said impinging members adapted to bias said members inwardly to permit gizzards to be held lightly between said opposed impinging members upon the release thereof from guide means, knife means positioned in said frame adjacent said wheel and adapted to intersect said gizzard during the circumferential movement thereof, and washing means positioned adjacent said wheel and in the path of movement of said gizzard holding stations.

9. In a gizzard splitter and washer, a frame, a wheel rotatably mounted in said frame, power means operatively connected to said wheel to cause the rotation thereof, a plurality of gizzard holding stations positioned on the outer periphery of said wheel, a plurality of impinging members positioned about the circumference of said wheel, said impinging members being positioned in opposed pairs adapted for horizontal outward movement in

40 relation to each other, spring means adapted to bias the impinging members inwardly toward each other, peg means on said impinging members, guide means positioned about a portion of the circumference of said wheel, and fixedly positioned in the path of movement of said

45 peg portions of said impinging members, whereby said impinging members will be held outwardly from the plane of said wheel to permit the insertion of gizzards therebetween, knife means positioned adjacent said wheel about the circumference thereof at a distance from said guide means, and washing means mounted adjacent said wheel on said frame at a point further removed about the circumference thereof in relation to said aforementioned

50 guide member, a second guide means further circumferentially beyond said washing means and further adapted to engage said previously mentioned pegs to cause the opening of said impinging members, whereby gizzards may be inserted between said impinging members adjacent said first mentioned guide means, thence moved circumferentially adjacent said knife, thence circumferentially adjacent said washing means, thence circumferentially adjacent said second guide means, whereby said gizzard will be released in relation to said impinging members.
